(57) **CLAIM**

The ornamental design for a barrow, as shown and described.

DESCRIPTION

FIG. 1 is a first perspective view of a barrow showing my new design;

FIG. 2 is a front view of the barrow of FIG. 1.

FIG. 3 is a right side view of the barrow of FIG. 1;

FIG. 4 is a rear view of the barrow of FIG. 1;

FIG. 5 is a left side view of the barrow of FIG. 1.

FIG. 6 is a top view of the barrow of FIG. 1.

FIG. 7 is a bottom view of the barrow of FIG. 1; and,

FIG. 8 is a second perspective view of the barrow of FIG. 1.

The broken lines in the drawings are included for the purpose of illustrating environment and form no part of the claimed design.
